KNITTING MACHINE

Kenneth Howie, Norristown, Pa., assignor to
Wildman Mfg. Co., Norristown, Pa., a corpora-
tion of Pennsylvania

Application January 11, 1938, Serial No. 184,465

19 Claims. (Cl. 66—96)

The invention concerns mechanism for making open work designs in fabric produced on knitting machines and in which the designs may be varied according to the setting of controlling elements on a lace wheel or like carrier called into action by a cam on the main cam shaft when this is shogged into narrowing position.

The invention concerns also means by which in addition to the open work, by which the fabric may present ornamental designs, other open work areas may be formed giving, for instance, the gauge of the fabric and other data of a utilitarian character such as the number of yarns used in the formation of the stocking blank.

The invention consists in the features and combination and arrangement of parts herein-after described and particularly pointed out in the appended claims.

In the drawings

Figure 1 is a front view of a portion of a full fashioned knitting machine generally of the single head type such as is disclosed in Letters Patent of the United States granted to Howie et al. on December 4, 1934, No. 1,982,991, though it will be understood that the invention is not restricted in its application to any particular type of full fashioned machine, whether of the multiple head type or single head type. Nor is the invention restricted to whether or not the machine is of the single unit type. Some of the mechanism ordinarily employed in a full fashioned knitting machine, though used in my machine as in prior practice, is not illustrated or described herein, because those skilled in this art will understand the construction and operation of my improvements without a disclosure herein of those old features.

Figure 1a is a detail view of the bracket which supports the hanger of the special transfer point.

Figure 1b is a detail view of the special transfer point.

Fig. 2 is a side view looking from the right hand side of Fig. 1.

Fig. 2a is a detail view of pawl and ratchet means.

Fig. 3 is a plan view of part of the variable lace design mechanism and associated elements being shown partly in section.

Figs. 3a and 3b are views of details of Fig. 3.

Fig. 4 is a detail vertical sectional view of the lace or picot bar and a special one *a* of the loop transfer point series.

Fig. 5 is a sectional view of the lace or picot bar and its carrying arm.

Fig. 6 is a side view of the special transfer point and its support, and the means for determining the position of said special point and its support.

Fig. 7 is a front view of certain of the parts located at the right hand upper part of Fig. 1.

Fig. 8 is a view of details associated with the picot or lace bar which is shown in vertical section.

Fig. 8a is a detail view.

Figs. 9 to 17 inclusive are diagrammatic views of the needles, sinkers, knock over bits and loop transfer point, in different positions assumed by them in performing a loop transfer operation.

Fig. 18 is a diagram of one form of design that the mechanism will produce.

The lace mechanism is intended to produce a pattern extending throughout the width of the fabric or by suitably disposing the lace points in the lace bar the lace work design can be produced at any particular point or points across the fabric.

I employ and control a lace bar whose points are disposed at locations along said bar at distances apart sufficient to permit variations in the design by automatically adjusting the said lace bar to make its points cooperate, according to the prescribed pattern, with various needles of predetermined sections of the needle row. Thus, as an example, the transfer points of the lace bar may be separated from each other a distance 20 equal to sixteen needle spaces, the position of the bar being determined by pins of various lengths in a lace or pattern member associated with the lace bar, said pins being set in predetermined positions according to the prescribed pattern and 30 being controlled by connections extending from the cam shaft A of the machine.

One example of designs that may be made is as follows: After making the picot edge at the turn of the welt a series of holes may be made 35 in the fabric representing, for instance, the sign 3—45 readable in the direction of the length of the knitted wales.

The numeral 45 would indicate the gauge and the numeral 3 would indicate the number of the 40 yarn used in knitting the fabric. Following the formation of the welt, and immediately below the same, the design in the single layer of fabric may assume various patterns. As an instance there may be rows of holes extending in the direction of the course of knitting, i. e. across the 45 fabric. These rows of holes would be parallel and spaced apart in the direction of the length of the fabric and between them the design, as an instance, may include rows of holes extending 50 diagonally of the fabric either simply parallel with each other, or crossing each other to produce a diamond shaped form of design, and these rows of holes may be interspersed with segregated holes.

The sign made up of the numeral 3, the dash and the numeral 45 or other insignia, is made by a special one of the picot points which is maintained in position to cooperate with a limited number of needles of the needle row while 60

the remaining transfer points a^1 of the picot or lace bar are dropped back out of operation relative to the needles. This special picot or transfer point is shown at a . More than one of these special points may be employed to make signs or insignias at various segregated restricted areas located at various points across the fabric.

When rows of openings are to be made in the fabric such as picot or lace work using all of the transfer points, namely, the special point or points a and all of the usual points a^1 , then the picot bar is moved forwardly from the position shown in Fig. 4 to a position in which all of the transfer points a^1 are in the same vertical plane with the special point or points a which latter then become one of the row of evenly spaced transfer points for making picot or lace work.

For setting the picot or lace bar 1 to make available either the insignia point or points a or the row of picot or lace points a^1 the following mechanism is employed; a shiftable cam bar a^2 is slidable lengthwise leftward Fig. 3 through suitable bearings, such as at a^3 , and in doing so will be moved towards the front of the machine by the inclined cam surface a^4 thereon working against the adjacent edge of the bearing a^3 . This movement of the cam bar will move the picot bar from the position shown in Fig. 4 where the picot points a^1 are idle to a position where they will occupy their working position relative to the needles, and in which position they will line up with the special point or points a to form a complete unbroken row of transfer points.

For this positioning of the picot bar by the cam bar a^2 adjusting screws a^5 Fig. 5 are mounted in the hangers 3 of the picot bar and bear upon the front face of the slidable cam bar a^2 so that as the slide bar moves bodily forward and backward, i. e. in a direction transverse to its length, the picot bar will be adjusted accordingly, and by adjusting the screw or screws a^5 accurate setting of the picot bar relative to the needles will be attained. The cam bar a^2 has a roller a^6 , Fig. 3 contacted by an inclined face b^1 of a cam track arm b pivoted at b^2 to a fixed frame member b^3 , Figs. 2 and 7 and moved to operative position by arm b^4 of a lever pivoted to the frame at b^5 , the other arm b^6 of said lever bearing on the edge of a cam disc c having high and low surfaces c^1 , c^2 , said disc being fixed on the hub 26^a , Fig. 3, having a drive fit with the hub 26^b of the pattern wheel 26 . This cam disc is made of two parts held together by screws c^3 Fig. 3 passing through slots into the hub 26^a . The sliding cam bar a^2 is guided by a tongue and groove connection at a^7 Figs. 1 and 3.

When the lever arm b^6 is riding the high surface c^1 of the cam disc c the cam arm b is maintained in operative position relative to the roller a^6 of the cam rod a^2 and consequently during the narrowing dip of the narrowing frame 47 the cam bar a^2 is moved leftward, it being understood that said cam bar is carried by the narrowing frame and hence the cam incline a^4 , of which there may be a number distributed along the cam bar, will cause the said bar to be moved at right angles to its longitudinal axis, or bodily towards the front of the machine, and hence through the adjustment screws a^5 one of which is shown in Fig. 5 the picot bar will be moved forward i. e. towards the front of the machine to set the picot or lace points a^1 in cooperative relation to the special point or points a to take off loops from the needles and replant them on other needles for making the prescribed design

by leaving openings in the fabric at the prescribed locations.

On the other hand, while the said lever b^6 is riding on the low cam edge c^2 of cam c the inclined cam portion b^1 of the cam arm b is positioned out of line with the roller a^6 of the cam bar a^2 , this effect being due to the spring b^7 drawing the said cam arm b aside from the path of the roller a^6 as this moves downwardly with the narrowing frame to bring its stop b^8 against frame stop b^9 Figs. 2 and 7. This allows the said cam bar a^2 to remain in its extreme right hand and rearward position of Fig. 3 with those points a^1 of the picot or lace bar out of working relation to the needles as in Fig. 4. This cam bar a^2 is subjected to the action of spring a^8 Fig. 1, which stresses it rightward in the position shown in Fig. 3, and also to the action of a plurality of springs, one of which is shown at a^9 in Fig. 3, which press said bar rearwardly to inoperative position when the cam incline a^4 of the bar is no longer contacting the edge of bearing a^3 and the picot bar will then assume its rearward position relative to the needles at which the picot points a^1 will be in inoperative position, whereas the special point or points a will maintain its or their operative position relative to the needles.

The special transfer point or points are mounted on a hanger d pivoted at its upper end at d^1 Figs. 4 and 6 to a brackets d^2 fixed to the picot bar.

The hanger d is provided with adjustment screws, the lower one d^3 , Fig. 6 contacts the face of picot bar to accurately adjust its relation to the special picot point a so that when the picot bar is in its forward position, its points a^1 will align with the said point a to provide a complete series of points equally spaced apart along the bar and all in the same relation to their respective needles. The upper adjustment screws d^4 of the said hanger d contacts a wear plate plate d^5 mounted on the fixed bar d^6 of the narrowing frame, which sets the special transfer point, or points, if more than one is used, in proper position relative to the needles, under pressure of the leaf spring d^7 at all times.

The hanger d of the special transfer point is pressed to proper position relative to the bracket d^2 upon which it is pivoted and guided by the use of laminated leaf spring d^7 .

The operation of one complete cycle of the narrowing head necessary to produce a given hole or set of holes in the design required is as follows:

With the picot bar, through its associated mechanism, resting against a pin in the pattern wheel 26 , and the cam lever b in a position whereby the roller a^6 on the end of the movable bar a^2 has contacted therewith, hence placing the complete picot bar with all its points in an operative position; the narrowing mechanism is tripped by the usual narrowing button on the regular pattern chain, causing the main cam shaft to be shogged into narrowing position; and the narrowing head to make its first dip, bringing the points of the picot bar, then in operative position, into a position to receive the loops from the needles which the particular length pin in the pattern wheel calls for. The loops having been received by the picot points from their respective needles, the narrowing head is raised to a point to permit the free passage of the points over the knock-over bits to accomplish the cross-over from the needle from which

the loop was received to the one to which said loop is to be delivered. This delivery having been made, on the second dip of the narrowing head, it (the narrowing head) is now ready to make it up or final movement of the cycle.

During this upward movement, after the picot points have been sufficiently raised to not meet any obstruction from the knock over bits or singers, the picot bar, through the yoke 18, mounted on the vertical shaft, and other associated mechanism, is moved into its extreme left hand position, after which the indexing of the pattern wheel occurs, bringing the next pin in the series into line with the plunger which controls the position of the picot bar on its next dip.

It is understood that whether a single or successive dips of the narrowing head are desired, this control would be obtained by the arrangement of the narrowing buttons on the pattern chain, and that after a single or multiple number of dips have been accomplished, the main cam shaft is returned to its normal or regular knitting position.

The movements of the narrowing head, when special point or points, only, are in operative position are identical with those above described, with the exception of the position of the cammed lever b, mounted on the hour'ng, which is withheld from its position where it contacts the roller a⁶ on the end of the movable bar a², thereby this bar remains in its back position, in turn holding the regular points of the picot bar in an inoperative position.

The lace or picot bar 1 carries the lace or picot points comparatively widely spaced apart, for instance, sixteen needle spaces, clamped in place by a section 2 against the main part of the bar. This bar is carried by arms 3 clamped by screws 4 to a rod 5 pivotally and slidably mounted in bearings 6 of the narrowing frame comprising arms 47 similarly numbered in said patent and likewise pivotally mounted as usual to the rear part of the frame of the machine to have up and down swinging movement, which is imparted thereto by links 47^a and lever arms 47^b as in usual practice. The picot or lace bar is stressed by a spring 7 to move to the right, Fig. 1 when free to do so, said spring bearing at one end on a part of the arm 8 in which the rod 5 is free to slide and turn. This arm 8 is fixed to a frame rod 9, fixed in the narrowing frame. The spring 7 at its other end bears on a collar 10 fixed to said rod 5. The rod 5 also has an arm 11 fixed thereto which carries a finger or projection 12 contacting a plate 13 on a plunger or rod 14 mounted slidably through a bearing 15 on the fixed frame, and stressed rightward by a spring 14^a, guided by a pin 14^b, Figs. 1, 3 and 7, and having a projection or finger 16, adapted to be contacted by a projection 17 on a yoke 18 having an upper arm and a lower arm 18^a, connected together as shown in Fig. 2 by a vertical portion 18^b. This yoke is loosely mounted to turn on the vertical shaft 20. The lower arm 18^a of said yoke has connected thereto pivotally a link 21, said link being pivoted to a lever 22 pivoted to the frame at 23 and operated by a cam 24 on the main cam shaft.

By this mechanism the picot bar is given a movement leftward Fig. 1 preparatory to the particular setting or position it is to assume under the action of the spring 7 pressing it rightward in Fig. 1 against one of a series of stop pins 25 adjustably mounted in a lace or pattern member

26, preferably in the form of a wheel. This wheel is turnable step by step about an axle 27. The indexing of this lace pattern wheel takes place while the picot or lace bar 1 is at the extreme leftward limit of its movement, viewed from the front of the machine, Fig. 1.

This wheel 26 has a ratchet portion 28 and a series of openings corresponding to the number of ratchet teeth. These openings receive the pins 25 which are of varying lengths according to the pattern to be formed in the knitted fabric, and they extend with their axes parallel with the axis of the pattern wheel.

They are brought in succession by the step by step rotary movement of the pattern wheel to a point where they are in line with a tooth or projection 30 on plunger or rod 14 so that when the picot bar returns in the right hand direction, Fig. 1, by the spring 7, after having been moved as above stated, to its extreme leftward position, it will be arrested by contacting the active pattern pin 25 of the lace wheel which, according to the prescribed plan is now in position opposite the projection 30 above mentioned on the plunger 14, and thus by the stopping of this plunger 14 will, through the connections before described, i. e. plate 13, adjustable finger 12, bracket or arm 11 and picot bar carrying rod 5, the picot bar will be arrested and its position in relation to the needles will be determined according to the pattern prescribed by the various lengths of pins 25 of the lace wheel.

The pins 25 are slidably mounted in the lace or pattern wheel 26 and the movement of the pins towards the right Fig. 3 is limited by contact of said pin with a lever 31 loosely mounted to turn about the shaft 20 and having an end 32 provided with an adjustable stop screw 33 adapted to bear on a fixed part of the structure such as the bracket 34 which supports the pattern member or wheel and associated parts. Thus the position of the active pin 25 or the pin which for the time being is acting as a stop for determining the rightward position of the picot or lace bar, and consequently the lace bar is accurately positioned.

The position of the picot bar along the needle row to make its points register with particular needles according to the pattern having been determined by the pattern pin of the lace wheel acting as a stop for said lace or picot bar, the fashioning frame is now ready to make its first dip for taking off loops from the needles according to the prescribed plan so that these loops can be transferred along the needle row and deposited on other needles, leaving those needles from which loops have been taken, bare or devoid of loops, thus to leave openings in the fabric for producing the design desired. Desirably this shifting of the loops along the needle row and their deposition upon other needles takes place, in the form of the invention shown as illustrative of its principles, upon the needles adjacent those from which the loops have been taken by the picot or lace points.

This one needle movement of the picot or lace bar is derived from a cam 24^a at the extreme right hand end of the main cam shaft A, Fig. 1 when said shaft, as is usual in ordinary practice, is shogged into position for narrowing. This cam operates a lever 35, Fig. 2, pivotally mounted on the ordinary rock shaft 36 and connected by a link 37, which in turn is connected to a bell crank lever 38 pivoted at 39 to the frame work of the machine and having its upper end contacting an

arm 40 fixed to the lower end of the vertical shaft 20.

This vertical shaft is mounted in a bracket 34 mounted on the fixed frame. It has an arm 42 fixed thereto at its upper end carrying an adjustment screw 43 contacting with the two armed lever 31—32 which, as before described, limits the movement of the pattern pins of the lace or picot pattern wheel. The operation of the vertical shaft 20 as just described, effects the shifting of the picot bar one needle space through the medium of its upper arm 42 acting through the lever 31, the slidable pattern pin 25, and the connections operated thereby leading to the bar carrying the lace points.

For indexing the lace or pattern wheel 26 step by step a pawl 44 engages the ratchet teeth 28 of the lace wheel. This pawl is pivotally mounted at 44' on an arm 45 pivoted at 46 to the pattern wheel bracket 34. The pawl is held yieldingly in engagement with the ratchet wheel by a spring 46.

This pawl carrying arm is operated by an arm 41 fixed on the vertical shaft 20 and a spring 45, Fig. 2a. The indexing of the pattern wheel occurs during the return movement of the vertical shaft, and while the picot bar is at its extreme position to the left.

The dips of the narrowing frame are the regular ones well known in the art, brought on by the usual pattern chain, which also initiates the shogging of the main cam shaft at the periods needed, and it will be understood that the lace mechanism described herein functions in timed relation therewith.

The picot or lace bar of the present invention is mounted on the regular narrowing frame having the usual narrowing movements, being brought into action as usual by buttons on the pattern chain.

With the particular pattern mechanism shown herein the first operation that takes place in connection with the picot or lace bar is the formation of the usual picot at the turn of the welt. Due to the particular degree of spacing of the picot or lace points as disclosed herein the picot is formed by eight successive dips of the narrowing machine.

After the welt is turned the lace design is produced. This may consist of spaced apart rows of holes like those occurring at the picot line, and between these two rows of closely set holes, the design may consist, for instance, of diagonal rows of holes i. e. at an inclination to the wales and spaced apart across the fabric. This design is made by two successive dips of the narrowing frame for each line of holes in any given course, due to the points being spaced sixteen needles apart on the lace bar and the holes only eight needles apart, the relative position of the holes being predetermined by the lengths of the pins in the pattern wheel. The same principles apply to other forms of design, for instance, with rows of holes extending diagonally of the fabric and crossing each other.

The picot bar 1 is held in proper relation to the slidable cam bar by a keeper Figs. 1 and 8, consisting of a small plate 49 having a finger piece 50 by which it may be raised to release the picot bar, so that the latter may be swung up to the idle position around the axis of the rod 5, Figs. 1, 4, 5 and 8.

This keeper has a vertical slot 51 which will enable it to be raised, and a leaf spring applies retaining pressure to this keeper to hold it in

lifted position to enable the picot bar to be swung up as above stated.

The keeper is supported by a screw 52 passing through the slot 51 into a bracket 53 which has a portion lying against the back of the keeper into which the screw 52 goes, and a portion attached by a screw 54 to the cam slide rod a². When the keeper is in its low position the picot bar 1 and the cam bar a² are virtually connected by the bracket 53 to move backwardly as one body under the pressure of the springs a⁷ and the points a¹ will then occupy the position shown in Fig. 4.

In Fig. 8 is shown a stationary cam member a³ like that shown in Fig. 3 for moving the cam bar a² laterally of itself forward or backward when said cam bar is moved lengthwise. This cam is fixed to the frame bar d⁶ by a screw 56 passing through a member 57 on the front side of the frame bar d⁶. This member has a hollow boss 58 in which there is a spring pressed button like that at a⁷ Fig. 3 for pressing the cam bar rearwardly and act as detaining means for said bar.

The invention is not limited in its application to full fashioned machines as it may be employed for making only the upper part of the stocking blank.

Neither is the invention limited to the employment of the special loop lifting point as the row of points may be made up of a complete set 30 of points all fixed in alignment in the picot or lace bar. In the latter case the sliding cam a² and other features attendant upon the use of the special point a¹ would be omitted.

The stop pins are limited in their movement 35 to the left in Fig. 3 by plates 25^a secured to the carrier-wheel 26 and engaging in notches in the lower sides of the stop pins Fig. 3.

The relation of the picot points in their various positions with those of the needles, sinkers 40 and knock over bits is like that of the narrowing points during a narrowing operation and are disclosed in Fig. 9 to Fig. 17 inclusive. At Fig. 9 we see the picot point a¹ in its extreme up position and the needle in the position where yarn 45 is being delivered, prior to knitting the next fabric course, the knitted fabric laying on top of knock over bits and under sinker. After this new course has been knit and the narrowing head tripped, the narrowing head dropping faster than 50 the needle bar, we find the needle and picot point each partly buried in the other's eye as shown in Fig. 10 which permits both to pass through last loop of fabric on needle as shown in Fig. 11, after which needle bar continues to 55 drop withdrawing the needle from the fabric which is now held by picot point, see Fig. 12. Both the needle and the picot point are then raised, sinkers being withdrawn, until point of the picot point clears the top of the knock over bit as shown in Fig. 13, this clearance permitting the point a¹ to be shifted laterally to the adjacent needle to the left, after which as in Fig. 14, both needles and picot points are ready to make the downward stroke when the needle and the 60 point again embrace as shown in Fig. 15 and the sinker comes forward ready to strip the fabric from the points onto the needle adjacent to one from which the loop was originally taken. The picot points are then raised to the extreme up 65 position and the needle bar more slowly raises toward its up position as shown by Figs. 16 and 17, after which the sinkers fully recede ready to be advanced by the jacks on the next yarn feed.

The pattern wheel may be restrained to the 75

desired degree in its movement by a friction plate 27^x adjustable by screw 27^y.

I claim:

1. In combination in a flat knitting machine, 5 a needle bar carrying a straight row of needles, a bar carrying points for transfer of loops from one needle to another along the needle row, means for moving the transfer bar a maximum distance along the needle row in one direction 10 and for moving the said bar in the reverse direction, and pattern means for stopping the said reverse movement of the bar variably, comprising a carrier, members movably mounted in said carrier, means for operating said members relative to the carrier, and means for giving said bar dipping movements to take off loops from needles and place them upon other needles, leaving openings in the fabric, substantially as described.

2. In combination in a knitting machine a 20 needle bar having a straight row of needles, a bar having points for removing loops from and placing them on needles of the row, means for giving the said bar a full movement in one direction, means for operating the bar in the reverse 25 direction, a series of stops, a carrier in relation to which said stops are differently disposed for variably limiting the reverse movement of said bar, and means for operating the carrier step by step, including a cam shaft and a cam thereon, 30 said stops being brought seriatim to a station by the step by step movement of the carrier for arresting the reverse movements of the bar, a dipping frame for giving dipping movements to the bar, said stops being movably mounted in the carrier, and adjustable means for arresting said 35 stops, and thereby arresting the movement of the point carrying bar to register its points with the needles.

3. In combination in a knitting machine a 40 straight row of needles of a flat knitting machine, a bar having loop lifting and restoring points, one of which is misaligned relative to the other points, a dipping frame, hangers pivoted to said frame and carrying said bar, a support for 45 the misaligned point movably mounted on said bar, a cam on the dipping frame for controlling the position of said bar to make its points align with the special point, or to occupy a position in rear thereof, and a stop on said dipping frame 50 for determining the position of the special point support relative to said bar.

4. A knitting machine according to claim 3 in which the cam means comprises a sliding bar movable in a direction lengthwise of the row of 55 points.

5. A knitting machine according to claim 3 in which the cam means comprises a sliding bar movable in a direction lengthwise of the row of points, and means rendered effective by the dipping frame for operating said sliding cam bar.

6. A knitting machine according to claim 3 in which the cam means comprises a sliding bar movable in a direction lengthwise of the row of 60 points, and means rendered effective by the dipping frame consisting of a cam against which the sliding bar works as the frame dips.

7. A knitting machine according to claim 3 in which the cam means comprises a sliding bar 70 movable in a direction lengthwise of the row of points, a cam mounted on the fixed frame for slidably operating said bar as the dipping frame moves down, and rotary cam means for setting said last mentioned cam into and out of operative position.

8. In combination in a knitting machine, a bar carrying a straight row of needles, a special loop lifting point forming one of a row of such points but normally misaligned in respect thereto, a bar carrying said loop lifting points, a dipping frame carrying said point bar, a sliding cam on said dipping frame for controlling the relative positions of the special point and the other points of the row, a cam mounted on the main frame shiftable from an idle position to a position in which it will operate the sliding cam as a consequence of the said slideable cam bar moving downwardly with the dipping frame, means for shifting the point carrying bar a maximum distance in one direction along the needle row, a series of stops 10 for variably limiting the return movement of said point carrying bar, a carrier for said stops, means for operating the said carrier step by step to bring the stops seriatim to position for arresting the return movement of the point carrying bar and rotary cam means moving in unison with the carrier for the stops, for setting said shiftable cam in operative or in idle position, substantially as described.

9. In combination in a knitting machine a 25 straight row of needles, a set of picot or lace points, a bar carrying said points, means for giving a maximum movement to the said point carrying bar lengthwise of the needle row in one direction, means for variably arresting the return movement of said bar, comprising a series of differently positioned stops, a carrier for said stops in which they are slidably mounted, to have limited movement, a cam shaft, a cam thereon, and connections from said cam to the stops to operate the same for giving the point carrying bar a movement along the needle row to a position for restoring the loops removed from the needle row back onto said needle row for making picot or lace work, substantially as described. 40

10. A knitting machine according to claim 9 in which the said connections include a lever to which the carrier brings the stops seriatim, substantially as described.

11. A knitting machine according to claim 9 45 in which the said connections include a lever to which the carrier brings the stops seriatim, and an adjustable lever interposed between the first mentioned lever and the stops for accurately determining the initial position of the stops.

12. A knitting machine according to claim 9 in which the said connections include a lever to which the carrier brings the stops seriatim, a rock shaft to which said lever is fixed, and an adjustable lever mounted to turn on said rock shaft and having one end interposed between the lever first mentioned and the stop for determining the initial position of said stops, substantially as described.

13. In combination in a knitting machine a 60 needle bar having a straight row of needles, a picot or lace bar carrying loop transfer points, a dipping frame carrying said bar, a vertically disposed rock shaft, a member loosely mounted on said rock shaft for moving said transfer point 65 bar a maximum distance in one direction along the needle row, means for moving the said bar in the reverse direction, a step by step movable carrier, stops of various lengths slidably mounted in said carrier, said stops limiting variously the 70 reverse movement of said bar, a lever arm fixed to the rock shaft for giving said bar a loop transfer movement along the needle row by sliding the stop, aligned therewith, in the carrier, a pawl for moving the carrier step by step, an arm on 75

- the rock shaft for operating said pawl, a cam shaft, connections operated by a cam means on said cam shaft for operating the rock shaft and connections operated by the cam shaft for operating the member loosely mounted on the rock shaft substantially as described.
14. In combination in a flat knitting machine, a needle bar having a straight row of needles, a bar having points for lifting loops from and restoring them to the needles of the needle row, means for supporting a plurality of the points in fixed relation to each other, whereby they are movable as a group into or out of alignment with a special point, said special point being immovable whereby it will always cooperate with a needle to move and restore a loop of the needle row, means for moving said plurality of points as a group into the disaligned relation in which they occupy a position in a vertical plane to the rear of the special point, whereby they will perform idly while the special point operates to remove and restore a loop of the needle row, or into the aligned relation, for unison operation in removing loops from and replacing them upon the needle row, and means for giving dipping movement to said bar, substantially as described.
15. In combination in a flat knitting machine, a needle bar having a straight row of needles, a bar having points for lifting loops from and restoring them to the needles of the needle row, a special one of said points being operative for removing a loop from the needle row, and restoring it to the needle row while other points of the bar perform idly, means for aligning said other points and the special point for unison operation in removing loops from and replacing them upon the needle row, means for giving dipping movement to said bar, a support for the special point mounted on the said point carrying bar and in relation to which said point carrying bar is movable, means for maintaining the special point support in position with the special point in normal position relative to the needle, and cam means for setting the point carrying bar in position to align said other points with the special point to complete the row or to set the point carrying bar rearwardly away from the special point to render said other points idle, substantially as described.
16. In combination in a flat knitting machine, a needle bar having a straight row of needles, a bar having points for lifting loops from and restoring them to the needles of the needle row, a special one of said points being operative for removing a loop from the needle row, and restoring it to the needle row while other points of the bar perform idly, means for aligning said other points and the special point for unison operation in removing loops from and replacing them upon the needle row, means for giving dipping movement to said bar, a support for the special point mounted on the said point carrying bar and in relation to which said point carrying bar is movable, means for maintaining the special point support in position with the special point in normal position relative to the needles, and cam means for setting the point carrying bar in position to align said other points with the special point to complete the needle row or to set the point carrying bar rearwardly away from the special point to render said other points idle, said

support for the special point being pivotally mounted, and the maintaining means including a member relatively fixed acting as a stop for said pivotally mounted support.

17. In combination in a flat knitting machine, a needle bar having a straight row of needles, a bar having points for lifting loops from and restoring them to the needles of the needle row, a special one of said points being operative for removing a loop from the needle row, and restoring it to the needle row while other points of the bar perform idly, means for aligning said other points and the special point for unison operation in removing loops from and replacing them upon the needle row, means for giving dipping movement to said bar, a support for the special point mounted on the said point carrying bar and in relation to which said point carrying bar is movable, means for maintaining the special point support in position with the special point in normal position relative to the needle, and cam means for setting the point carrying bar in position to align said other points with the special point to complete the needle row or to set the point carrying bar rearwardly away from the special point to render said other points idle, said cam means comprising a sliding bar, substantially as described.

18. In combination in a flat knitting machine, a needle bar having a straight row of needles, a bar having points for lifting loops from and restoring them to the needles of the needle row, means for supporting a plurality of the points in fixed relation to each other, whereby they are movable as a group into or out of alignment with a special point, said special point being immovable whereby it will always cooperate with a needle to move and restore a loop of the needle row, means for moving said plurality of points as a group into the disaligned relation, whereby they will perform idly while the special point operates to remove and restore a loop of the needle row, or into the aligned relation, for unison operation in removing loops from and replacing them upon the needle row, and means for giving dipping movement to said bar, said bar being mounted for endwise movement longitudinally of the needle row, and means for shifting the bar endwise to bring the active point, or points, in alignment with designated needles from which the loop, or loops, are to be removed.

19. In combination in a flat knitting machine, a needle bar having a straight row of needles, a bar having points for lifting loops from and restoring them to the needles of the needle row, means for supporting a plurality of the points in fixed relation to each other whereby they are movable as a group into or out of alignment with a special point, said special point being immovable whereby it will always cooperate with a needle to remove and restore a loop of the needle row, means for moving said plurality of points as a group into the disaligned relation, whereby they will perform idly while the special point operates to remove and restore a loop of the needle row, or into the aligned relation for unison operation in removing loops from and replacing them upon the needle row, and means for giving dipping movement to said bar, substantially as described.

KENNETH HOWIE.
